[57] CLAIM

The ornamental design for a combined signal, emergency and safety warning light for trucks, as shown and described.

DESCRIPTION

FIG. 1 is a perspective view of a combined signal, emergency and safety warning light for trucks showing our new design, the truck being shown in broken lines for illustrative purposes only;

FIG. 2 is a perspective view thereof on an enlarged scale;

FIG. 3 is a rear elevational view thereof on an enlarged scale;

FIG. 4 is a side elevational view thereof on an enlarged scale;

FIG. 5 is a front elevational view thereof on an enlarged scale, the truck being shown in broken lines for illustrative purposes only;

FIGS. 6 and 7 are, respectively, bottom and top plan views thereof on an enlarged scale.
